UNITED STATES PATENT OFFICE.

WILLIAM N. SEWELL, OF WINCHESTER, KENTUCKY.

METALLIC RAILROAD-TIE.

1,113,841.

Specification of Letters Patent. Patented Oct. 13, 1914.

Application filed December 12, 1913. Serial No. 806,341.

To all whom it may concern:

Be it known that I, WILLIAM N. SEWELL, a citizen of the United States, residing at Winchester, in the county of Clark and State 5 of Kentucky, have invented certain new and useful Improvements in Metallic Railroad-Ties; and I do hereby declare the following to be a full, clear, and exact description of the invention, such as will enable others 10 skilled in the art to which it appertains to make and use the same.

This invention relates to improvements in cross ties, and an object of the invention is to provide a cross tie formed of interlocking members so arranged and proportioned that as the load increases upon the rail the tie will serve to grip the same more tightly.

A further object of the invention is to provide a tie which shall have formed integral therewith or secured thereto, means for engaging the flange of the rail, the said means being disposed so as to coöperate with inclined portions of the cross tie for assisting the action of locking the tie and rail.

25 A further object of the invention is to provide a tie of such construction as will enable ballast to be located within the tie and serve to form a permanent part of the road bed as well as support and strengthen 30 the cross tie.

With these and other objects in view, the invention comprises certain novel constructions, combinations and arrangements of parts as will be hereinafter more fully described and claimed.

In the accompanying drawings, wherein similar reference characters designate corresponding parts: Figure 1 shows a perspective view of one half of the tie; Fig. 2 shows 40 a perspective view of the other half of the tie coöperating with the half shown in Fig. 1; Fig. 3 is a top plan view of the two halves shown in Figs. 1 and 2 assembled and ready for the reception of the rail; Fig. 4 is a top plan view of the tie after the same 45 has been expanded from the position shown in Fig. 3 after the reception of the rail; Fig. 5 is a perspective view showing a modified view of one end of the tie member; Fig. 50 6 is a perspective view showing an assembled tie having a modified form of securing means for holding the rail to the tie; Fig. 7 is a perspective detail view showing the bottom of one of the locking devices shown 55 in Fig. 6; Fig. 8 is a perspective view of a locking and sliding member which may be

used in connection with the modification shown in Fig. 5; Fig. 9 is a perspective view of the form of locking pin associated with the pin shown in Fig. 7 as used in the modification shown in Fig. 6.

The general aim of the present invention is to provide a cross tie for railroad construction which shall consist of two substantially complementarily formed halves having co-acting inclined planes formed thereon and having rail locking members either integral or secured to the halves and so disposed that when the co-acting inclined plane members are brought in contact and the halves slipped together, the rail locking means will be spaced to receive a rail, after which the separation of the halves will result in the permanent gripping of the rail by the locks.

Referring more particularly to the drawings, it will be seen that one-half of the tie is composed of a plate 1 forming the top of the half from which depends a flange 2 designed to form one edge of the completed tie, and in order to facilitate the assembly of the tie there is provided an elevated portion 3 formed in the top 1 and a second elevated portion 4 at the end, these raised portions being formed by striking the same 85 in a die or in any other suitable manner and being formed merely for the matter of convenience in assembling. Extending about half way more or less through plate 1 and at an angle to the sides thereof is an inclined slot 5, one side of which is formed by the edge 6 of the centrally elevated portion 3, while the other edge is formed by the lower section 7 of the top plate 1.

Spaced from the slot 5 and extending 95 within the lower section 7 substantially as shown in Fig. 1 is an opening 8 having a wall 9 inclined with respect to the sides of top plate 1, said wall 9 also being at an angle to the slot 5. If desired, the wall 9 100 may merge into the portion 10 substantially parallel to the sides of the plate 1 and terminate in a pocket 11, the walls 9 and 10 continuing to form an inclined edge 12, defining with the unflanged edge of the plate 1 105 a stud 13. Upturned from the plate 1 and adjacent inclined edge 9 is a rail flange lock 14 provided with an overhang 15 adapted to catch the flange of the rail and provided with a vertical portion 16, the purpose of 110 which will be described hereinafter. With the exception of the raised portion 4, the

ends of the half shown in Fig. 1 are identical and no further description of the same is deemed necessary. Referring now to Fig. 2 it will be seen that the other half of the 5 cross tie comprises a plate 17 which may be formed flat without elevated or offset portions or it may be formed identical with the half shown in Fig. 1 and each with an aggregation of offsets and having depending therefrom a flange 18 which serves to form the other side of the tie. Located centrally with respect to the length of the plate 17 and extending about half way across the plate is a slot 19, the walls of which are 10 substantially parallel to the walls of slot 5 when the two sections or halves are assembled. Spaced from the slot 19 is a stud 20 defined by an opening 21 formed in the plate 17 and having an edge 22 substantially 15 parallel to the edge 12 of the half shown in Fig. 1; said edge connecting with the pocket 23 from which extends an angular edge 24, which is at an angle to the slot 19 on the sides of the said plate 17. Secured to or 20 integral with the plate 17, but extending above the inclined edge 24, is a locking device 25 having an overhang 26 and a vertical edge 27 adapted to engage the inclined edge 12 of the plate 1. The formation of 25 the two ends of the plate 17 is identical and the description of one will suffice for both. When it is desired to assemble the tie, in order to place the same in a road bed, the two halves will be interlocked until the 30 raised portions 3 and 4 of the plate 1 overhang the corresponding portions of the plate 17, the end 28 of the plate 17, however, being formed so as to overlap the corresponding end plate 1. In order to accomplish this it 35 may be necessary to offset the end 28 except when the two halves are formed identical and have corresponding offsets or deflected portions. It will be noted that when the two halves are in relative position, shown in Fig. 40 3, the locking devices 14 carried by the plate 1 and the corresponding locking devices 25 carried by the plate 17 are spaced apart in maximum distances, this distance being sufficient to receive the flange of the rail. It 45 will be understood that in order to assemble the halves, as shown in Fig. 3, the studs 20 will be placed behind the locking devices 14 and the studs 13 will be placed in front of the locking devices 25, it being understood 50 that the vertical sides 16 will engage the inclined edges 22 and plate 17 while vertical edges 27 will engage the inclined edge 12 of the plate 1, so that as the plates are pushed together they are moved at an angle to the 55 axis of the tie. After the rail has been mounted upon the cross tie so that the overhanging portions 26 and 15 engage the flanges of the rail, these halves may be 60 spaced by filling the same with any suitable ballast, as by earth, rock or other material 65

used for constructing the bed of a road, and it will be apparent that the separation of the halves will be accompanied by a sliding of the vertical edges of the locking devices along their corresponding and adjacent inclined edges, for instance the vertical edge 27 will be constrained to move outwardly along the inclined edge 12 of the plate 1. It will be apparent from this action that the locking devices are 70 brought nearer together and the filling of the tie with ballast may continue until the locking devices have securely gripped the rail. It is apparent that each time a load is placed upon a track, or rail, 75 as by the passage of a train, the tie will be depressed and the natural consequence will be that the ballast within will be depressed, so as to expand against the flanges 2 and 18, which will result in the separation of the 80 halves of the cross tie, but it will be understood, as previously described, that this separation will result in a more firm gripping of the rail by means of the locking devices 14 and 25. (See Fig. 4). 85 90

The modified form of the invention, shown in Fig. 5, consists in bending out of place certain portions of the material which are entirely removed from the preferred form of the invention and other features described. Thus, the material forming the plate 29 is cut and has a portion thereof bent downwardly as at 30 sufficiently to pass under the upturned portion 31 which serves as the rail locking device and has its 95 sliding portion inclined, instead of being vertical as described in the preferred form. It will be understood that Fig. 5 shows one end of one-half of a tie. A portion of the metal forming the plate 29 is bent down to 100 form the lip 32 which serves to reinforce the portion of the plate carrying the locking device 31. There is also provided a stud 33 used for purposes analogous to the corresponding studs used in the preferred form, 105 and there is further provided an inclined plane or edge 34 which engages the locking device formed on the other half. Struck up from the plate 29 on each end thereof is a 110 plug 35 which may serve to form an additional locking device for the rail, and it will be understood that as the halves of the tie move laterally with respect to each other, at the same time that they move apart the locks 35 will act in the same capacity as the locking devices 31 to grip the rail more firmly. Another feature shown in Fig. 5, consists in deflecting or slightly bending downward that portion of the tie carrying the rail locking devices 31 and 35; and also in deflecting or slightly bending upward that portion of the tie carrying the stud 33 and inclined plane 34, to facilitate the assembly 115 120 of the tie. 125

A still further modification of the inven- 130

tion is shown in Fig. 6, where there are provided halves 36 and 37 having respectively flanges 38 and 39. The half 36 has the upper part thereof provided with a plurality of slots 40 disposed at an angle to the sides of the plate on one end of the half, while the opposite end of the other half 37 is provided with a plurality of openings 41.

Fig. 7 shows a bottom perspective of a lock 42 having a body 43 provided with an overhang 44 and having a depending lug 45, the sides of which are disposed at an angle to the sides of the body 43 and are designed to fit within the slots 40 and 41. One of these rail locking members is secured to one end of the half 37, while the other member is secured to the other end of the half 36, but it will of course be understood that any number of these rail locking devices may be applied to any one cross tie, where it is desired to use the tie in connection with switches or crossing tracks, and preferably, though not necessarily, the locking devices shown at 42 engage the outer edge of the rail.

While the locking devices 42 are secured upon one of the halves of the tie, the corresponding locking devices or rail gripping lock 46 is carried by the corresponding end of the other half of the rail tie, the lock 46 being shown in detail in Fig. 9, where it will be seen that the body 47 has projecting therefrom an overhang 48 and a shank 49 which may be provided with any suitable means for securing the same to the tie half carrying the same, or the shank may be rolled or riveted to the half to which it is secured. If for any reason it should not be desirable to use shank 49 there may be provided through the body 47 a bore 49' substantially parallel to the vertical edges of the lock 46 which may receive any suitable locking means secured to the cross tie. The holes in the halves of the tie indicated at 50 and 51 may be formed at the time the halves are manufactured and if desired additional openings or holes may be provided so that in the event of a break of one of the locking devices a second one may be inserted in one of the additional holes.

As shown in Fig. 8, there may be provided locking means having a base 52 and an upright 53 extending therefrom provided with overhang 54, the base being provided with an opening 55 for the reception of any suitable means for securing the auxiliary locking means to one or any of the halves of the tie, as shown in Figs. 1, 2, 3, 4 and 5. Also, as shown at 56, it will be entirely possible to extend the upper plate of the halves so that the same may be bent over to prevent escape of the ballast.

It will be apparent from the tie described herein that there is no possibility of the sections becoming disassembled while the rail is

in place, and that as the load is applied to the rails the tie will expand so as to cover a greater portion of the road bed and therefore distribute the weight, and all that is necessary to remove the tie from the rail is to jack the rail up until the halves of the tie are above the contained ballast, after which it will be a simple matter to draw the halves together, at which time the cam or inclined plane action will be such as to separate the securing means for holding the rail and the halves may be removed for any desirable purpose.

What I claim is:

1. A cross tie comprising complementarily formed sections inclined planes formed on the complementary sections, and rail gripping projections secured to each of said sections and adapted to engage the corresponding inclined planes of the other section.

2. A cross tie comprising two complementarily formed interlocking sections, inclined planes formed on each of said sections, rail gripping projections extending from each of said sections and adapted to engage the corresponding inclined planes of the other section, and means for moving the two sections longitudinally as said sections are drawn together.

3. A cross tie comprising complementarily formed sections, each of said sections being provided with an inclined slot extending substantially one half the width of the section, portions of each of said sections adapted to engage the inclined slots of the other section, and rail-gripping means carried by each of said sections.

4. A cross tie comprising complementarily formed sections, means adapted to move said sections longitudinally relative to one another as said sections are drawn together, and rail-gripping means rigid with the sections adapted to approach each other as the sections are drawn apart.

5. A cross tie comprising interengaging sections adapted to approach and recede one from the other, rail-gripping means carried by the sections, said sections adapted to draw the rail-gripping means together as the sections recede from each other.

6. A cross tie comprising complementary sections, substantially parallel edges provided on each cross tie section inclined to the length of the cross tie section, rail gripping means formed on each cross tie section adapted to engage the inclined edges of the other cross tie section and means for moving the cross tie sections longitudinally with respect to each other as they are separated, said rail gripping means engaging the inclined portions as the cross tie sections separate.

7. A railroad cross tie comprising complementarily formed sections substantially parallel inclined edges formed on each section,

an inclined slot formed intermediate the inclined edges, portions of each of said sections adapted to engage inclined slots of the other section, and rail gripping means rigid 5 with each section adapted to engage the corresponding inclined edges on the other section.

8. A railroad cross tie formed of complementary sections and being substantially U- 10 shaped in cross section, each section having an inclined recess adapted to engage a cor-

responding inclined recess in the other section, rail gripping means carried on each of the sections, the rail gripping means for any one rail adapted to approach as the sides 15 of the U-frame are separated.

In testimony whereof I affix my signature in presence of two witnesses.

WILLIAM N. SEWELL.
